UNITED STATES PATENT OFFICE.

HENRY DIETRICH, OF PITTSBURG, PENNSYLVANIA.

DESIGN FOR A LAMP-CHIMNEY.

SPECIFICATION forming part of Design No. 15,852, dated February 24, 1885.

Application filed January 17, 1885. Term of patent 7 years.

To all whom it may concern:

Be it known that I, HENRY DIETRICH, a citizen of the United States, residing at Pittsburgh, in the county of Allegheny and State of Pennsylvania, have invented and produced a new and original Design for Lamp-Chimneys, of which the following is a specification, reference being had therein to the accompanying drawing.

10 My design relates to lamp-chimneys and similar articles; and it consists in the ornamentation at the top of the lamp-chimney, above the edge thereof.

15 The principal feature of my design is an ornamentation for the top of the chimney; and it consists of a lamp-chimney having a circular edge and the representation of a cable or twisted bead raised above said edge.

20 In the drawing, A is the main body of the chimney, having the mouth or top opening, B, which is flared to give the graceful curve shown. Raised above the rim C is the ornamentation or cable D. This cable or ornamentation consists of a twisted thread of suit-

able material around the upper end of the 25 chimney, giving an ornamentation similar to the exterior surface of a cable or rope. The cable or ornamentation extends above the edge of the chimney, leaving the edge solid below the bead. The top of the chimney thus 30 presents to the eye the regular flared top of the ordinary lamp-chimney, and the cable ornamentation of the top, which is very pleasing in its effects.

Having thus described my design, what I 35 claim is—

The design for a lamp-chimney of the shape herein shown and described, consisting of the representation of a twisted or cable-like annular bead on the top of the chimney, as set 40 forth.

In testimony whereof I affix my signature in presence of two witnesses.

HENRY DIETRICH.
